H. F. GRUMAN

FEEDING MECHANISM FOR SEWING MACHINES

Filed Oct. 21, 1924

Inventor

H.F. Gruman,

S. George Tate

Attorney,

UNITED STATES PATENT OFFICE.

HORACE F. GRUMAN, OF ST. LOUIS, MISSOURI, ASSIGNOR TO LEWIS INVISIBLE STITCH MACHINE CO., OF ST. LOUIS, MISSOURI, A CORPORATION OF MAINE.

FEEDING MECHANISM FOR SEWING MACHINES.

Application filed October 21, 1924. Serial No. 744,917.

To all whom it may concern:

Be it known that I, HORACE F. GRUMAN, citizen of the United States, residing at St. Louis, and State of Missouri, have invented 5 certain new and useful Improvements in Feeding Mechanism for Sewing Machines, of which the following is a specification.

This invention relates to new and useful improvements in feeding mechanisms for 10 sewing machines generally, although more particularly to a top feeding mechanism.

It is a well known fact in this art that when feeding two superimposed fabrics through a sewing machine having a lower feed only, the lower ply being engaged by the usual 4-motion feed dog tends to feed faster than a superimposed ply which engages the presser foot. In other words the 15 upper ply is not directly engaged by the lower feed dog and consequently it has a tendency to drag. This disadvantage has been known and various top feed mechanisms have been constructed to overcome the objections stated.

25 In the patent to Thomas J. Hayes, No. 1,474,966, issued November 20, 1923, there is provided a top feeding mechanism which is in the nature of an attachment to the presser bar. This top feed is actuated from the needle bar through the medium of an oscillatory lever having a sliding pivotal connection with a stud carried by said needle bar. This construction necessitates the formation 30 of a fork at the front end of said actuating lever and this form is of such a length as to project in front of the needle bar and interfere with the hands of the operator and therefore constitutes a forwardly extending 35 projection which reciprocates at a high rate of speed and is therefore dangerous to the operator.

The principal object of my invention is to provide an improved construction over the Hayes patent above noted whereby the projection above described is eliminated and consequently all danger to the operator is avoided.

With the above and other objects in view which will more readily appear as the nature of the invention is better understood, the same consists in the novel construction, combination and arrangement of parts hereinafter more fully described, illustrated and claimed.

In the accompanying drawings which 55 show one form of my invention:

Figure 1 is a side elevation of a top feed mechanism constructed in accordance with my invention,

Figure 2 is a side elevation from the opposite direction,

Figure 3 is a view somewhat similar to Figure 2 but certain of the parts being removed to better disclose the construction.

Figure 4 is a horizontal sectional view 65 taken on the line 4-4 of Figure 1, and

Figure 5 is a detail sectional view taken on the line 5-5 of Figure 2.

Referring to the accompanying drawings, 70 5 designates the usual sewing machine head which carries a vertically reciprocatory needle bar 6 and a vertically disposed presser bar 7 which is arranged in rear of said needle bar. The needle bar 6 supports a needle 8 through the medium of a needle clamp 9, 75 the needle shank being clamped between the needle bar and the clamp by means of a clamping screw 10, which has threaded engagement through a stud 11 which projects laterally from the needle clamp 9 and is integral therewith. The screw 10 is provided with a head 12 having a diameter somewhat less than the diameter of the stud 11. Associated with the needle 8 is a throat plate 13 and the usual 4-motion lower feed dog 14. 85

The entire upper feed mechanism is carried in a presser foot frame 15 which includes a detachable presser foot 16. This frame is detachably supported on the lower end of the presser bar 7 by means of a set 90 screw 17. The frame 15 extends in rear of the presser bar 7 and carried by the upper rear end of said frame is a boss 18 in which is mounted a headed bearing stud 19 having its longitudinal axis disposed in a horizontal 95 plane and in a plane at right angles to the direction of feed, the stud being held against movement relative to the frame by means of a set screw 20. Journaled on the stud 19 between the head thereof and the boss 18 is a cam 21 which is oscillated by the needle bar to impart proper movements to a top feed dog 22.

The top feed dog 22 works through an opening 23 in the presser foot 16 and is pivoted at its rear end as at 24 to the lower end of a vertically disposed lever 25 fulcrumed intermediate its ends as at 26 to the frame

15, the fulcrum being located between the presser bar 7 and the cam 21. The top feed dog 22 is positively moved rearwardly to feed the material by reason of the lever 25 being oscillated through the medium of the cam surface 27 of the cam 21 engaging the upper end of the lever. The top feed dog 22 is automatically returned to its initial position, that is, moved forwardly, by means of a spring 28 which functions as stated upon withdrawal of the cam surface 27 from the lever 25.

The top feed dog 22 is also given up and down movements, the down movement being 15 positively imparted through the medium of a depresser lever 29 and the up movement being automatically imparted by the spring 28. The lever 29 is fulcrumed on the pivot 26 and the lower end thereof engages a shoulder 30 fixed to the top feed dog. The upper end of the lever is formed with a clearance slot 31 which encompasses the hub 32 of the cam 21. The cam 21 carries a laterally extending roller bearing stud 33 which cooperates with the cam-shaped upper portion 34 of the depresser lever 29. As the roller of the stud 33 rides up the appropriate cam surface of said lever 29, it rocks the upper end of the lever forwardly to a definite extent, causing the lower end of the lever to press down the top feed dog against the tension of the spring 28 and then as the roller rides along the surface 35 of said lever, it holds the latter down.

35 In order to oscillate the cam 21, I have provided a connection with the needle bar 6. This connection includes a telescopic actuating lever consisting of a rod 36 and a socket arm 37, the socket arm being integrally connected at its rear end to a laterally offset tail piece 38 which is journaled on the headed stud 19 and lies flat against the right hand face of the cam 21. A clamping screw 39 passes through a concentric slot 40 formed 40 in the tail piece 38 and has threaded engagement with the cam 21. Thus the actuating lever is positively connected to the cam 21 through an adjustable connection which permits the cam to be readily adjusted to vary 45 the length of feed travel of the top feed dog. The front end of the rod 38 is provided with a socket 41 which has pivotal

connection with the stud 11 of the needle clamp.

From the foregoing it will be apparent 55 that I have provided an actuating lever for the top feed dog which is actuated from the needle bar but which does not project in front thereof and consequently all danger to the hands of the operator is avoided; that the clamping screw for the needle clamp is covered by the socket which has pivotal connection with the stud fixed to the needle clamp; that the socket arm of the telescopic actuating lever is offset from the tail piece whereby the cooperating rod will have freedom of movement and whereby a construction is provided which will permit of the bore being readily drilled and reamed, and that by means of the adjustable connection between the tail piece of the actuating lever and the cam the feed travel of the top feed dog may be readily adjusted.

Without further description it is thought 75 that the many features and advantages of the invention will be readily apparent and it will, of course, be understood that changes in the form, proportion and minor details of construction may be resorted to without departing from the spirit of the invention 80 or scope of the appended claim.

I claim:

In a sewing machine top feeding mechanism, the combination of a presser-bar, a vertically reciprocating needle bar located in front of said presser-bar, a needle clamp carried by said needle bar and having a laterally extending stud, a top feed dog, a frame carried by said presser-bar and located in rear of said needle bar, a cam 90 journaled on said frame, means operated by said cam for imparting feeding movements to said feed dog, and means for oscillating said cam consisting of a telescopic actuating lever having its longitudinal axis disposed parallel to the line of feed and comprising a rod and a socket arm, the rod having its outer end fixedly journaled on the stud of the needle clamp and the socket arm being positively connected to said cam.

100 In testimony whereof I hereunto affix my signature.

HORACE F. GRUMAN.
